UNITED STATES PATENT OFFICE.

ERWIN M. LURIE, OF OAK PARK, ILLINOIS.

FURRING DEVICE.

Application filed April 11, 1927. Serial No. 182,726.

This invention relates to furring devices adapted for securing a plaster supporting base, as metal lath, upon a wall or surface to be plastered and for similar purposes.

5 Stated generally, the object of the invention is to provide a furring device for the purpose specified, which will be simple in construction, effective for its designed purpose, and which may be manufactured at relatively small cost.

A specific object of the invention is to provide improved and simplified means for initially securing said furring devices to the studding or other supporting means, separate 15 from the means for securing the plaster supporting base or other structural material to the furring devices.

In accordance with my invention, furring devices for effecting the objects of the invention comprise stools, each comprising a portion supported in spaced relation to the studding or other supporting surface by a depending flanged portion, the outer ends of which are adapted to rest against said surface.

Furring stools embodying my invention and improvements also comprise the various features and details of construction herein-after described and claimed.

30 In the accompanying drawings in which the invention is fully illustrated,

Fig. 1 is a top plan view of one form of furring stool of my invention;

Fig. 2 is a plan view showing said stools 35 as applied in use for securing metal lath upon a wall or surface to be plastered;

Fig. 3 is a view from the right side of Fig. 2;

And Figs. 4 to 7 are views illustrating still 40 another form of stool embodying my invention.

Describing the invention with particular reference to the drawings and referring in the first instance, particularly to Figs. 1, 2 45 and 3, A designates a furring stool embodying my invention as a whole, comprising a flat marginal portion 1, a raised central portion 2 and an intermediate connecting portion 3. The raised central portion of the stool is 50 provided with a hole or opening 4 adapted to receive a nail 5 for securing said furring stool to the studding 6 of a wall or other surface to which plaster is to be applied.

As shown, a head 7 is formed on the nail 55 at a distance from its projecting outer end, say one-half to three-quarters of an inch.

The intermediate portion 3 of the furring stool, which connects the marginal and raised central portions thereof may be skeletonized by forming holes 8 therein, said intermediate 60 connecting portion thus consisting of spaced sections. My invention, however, contemplates continuous intermediate portions, if desired.

As shown, and in accordance with usual 65 building practice, building paper or other insulating covering 9 is applied to the studding 6.

In securing metal lath or other sheet material 10 to the studding 6, the furring stools 70 A are first secured to the studding 6 with their marginal surfaces resting in contact therewith or with the insulating covering 9, by means of the nails 5 which are inserted through the holes 4 in the raised portions 2 75 of said stools and driven into the studding until the heads 7 on the nails rest against the raised central portion 2 of the stool.

After securing said stools in position to the studding 6, the metal lath or other material is applied so as to rest in contact with the tops of the stools or with the heads 7 of the nails 5, the projecting outer ends 5' of said nails extending through the holes or openings in said metal lath, or other material. After the lath or other material is applied, it is secured in position by bending the projecting outer ends 5' of said nails 80 downwardly against the outer side thereof, as shown in full lines in Figs. 2 and 3.

As a modification of the invention, the furring stools, instead of being stamped from relatively thin, light sheet metal, as sheet steel, as in the case of my improved furring stools heretofore described, said 95 stools are made from sheet metal channels rolled from strips of sheet metal, preferably sheet steel, which is relatively much heavier and stronger than that used for making my improved furring stools heretofore described, 100 and cut cross-wise into pieces of desired length. A desirable size for this form of furring stool is, approximately, width $\frac{3}{4}$ "; length $\frac{5}{8}$ " and height $\frac{3}{8}$ ", and they can be manufactured at very low cost by cutting $\frac{3}{4}$ " 105 channel bars, rolled from stock of approximately 16 gauge—which can be purchased in quantities commercially—into pieces of desired length ($\frac{5}{8}$ ") and piercing the raised portions thereof with holes adapted to receive securing nails of desired size—preferably nails having heads formed at a distance 110

from their outer ends, as in the case of the stools shown in Figs. 1 to 3. Also, where building paper or other insulating covering is to be used, which might be penetrated or torn by the edges of the depending portions of said stools when the projecting outer ends of the securing nails are bent over against the outer side of the metal lath or other material, washers of thin metal, preferably tin, are preferably inserted between said stools and the building paper or other insulating covering, which will operate to distribute the pressure of said stools and thus prevent them from tearing or penetrating said building paper or other material, in an obvious manner.

Describing said modification with reference to the drawings, A⁴ designates the furring stool as a whole, comprising a portion 2⁴ formed at the edges of which are marginal flanges 17, the outer edges of which are adapted to rest in contact with the studding 6⁴, either directly, or where building paper or other insulating covering is used, as shown in Figs. 6 and 7 upon discs 18 of thin sheet metal, preferably tin, inserted between the outer edges of the marginal flanges 17 and said insulating covering.

Each of the stools A⁴ is pierced approximately at the center of its raised portion 2⁴ with a hole 8⁴ adapted to receive a nail 5⁴ for securing said stool and also the metal lath or other material to the studding, said nail as shown being similar to those shown in Figs. 1 to 3, having heads 7⁴ formed at a

distance from their outer ends, which are adapted to be bent over the metal lath or other material, as shown at 5⁵, thus securing the entire structure to the studding or other support.

I claim:

1. Furring comprising stools made of suitable sheet material, each comprising a seat portion and portions depending therefrom forming means for supporting said seat portion in raised position, and unitary means for separately and rigidly securing said stools to a supporting surface and sheet material to said stools, said stools and securing means forming separate parts.

2. Furring comprising stools as specified in claim 1, in which the seat portions of the stools are provided with holes and the securing means consists of nails driven into the supporting surface through the holes in said seat portions, heads formed on said nails at a distance from their outer ends providing means for separately securing said stools to the supporting surface, and the outer ends of said nails when bent laterally forming means for securing sheet material to said stools.

3. Furring as specified in claim 2, in which the furring stools consist of short lengths of metal channel bars secured to the supporting surface with the channels thereof disposed inwardly.

In witness that I claim the foregoing as my invention, I affix my signature this 6th day of April, A. D. 1927.

ERWIN M. LURIE.
